CLAIM

The ornamental design for a dilution dispenser, as shown and described.

DESCRIPTION

FIG. 1 is a perspective view of a dilution dispenser according to the principles of the present invention;

FIG. 2 is a front view of the dilution dispenser shown in FIG. 1;

FIG. 3 is a rear view of the dilution dispenser shown in FIG. 1;

FIG. 4 is a right side view of the dilution dispenser shown in FIG. 1;

FIG. 5 is a left side view of the dilution dispenser shown in FIG. 1;

FIG. 6 is a top view of the dilution dispenser shown in FIG. 1; and,

FIG. 7 is a bottom view of the dilution dispenser shown in FIG. 1.

The broken line showing of parts of the dilution dispenser is included for the purpose of illustrating use and environment and forms no part of the claimed design.
